UNITED STATES PATENT OFFICE.

HARRIE T. LINDEBERG, OF NEW YORK, N. Y.

DESIGN FOR A GATE.

51,500.

Specification for Design.

Patented Nov. 20, 1917.

Application filed July 20, 1917. Serial No. 181,912. Term of patent 14 years.

To all whom it may concern:

Be it known that I, HARRIE T. LINDEBERG, a citizen of the United States, residing at New York, in the county of New York and State of New York, have invented, a new, original, and ornamental Design for a Gate, of which the following is a specification, reference being had to the accompanying drawing, forming part thereof.

The figure is a view in elevation of a gate showing my new design.

I claim:

The ornamental design for a gate as shown.

HARRIE T. LINDEBERG.

Witnesses:

RUTH O'MEARA,
C. J. KULBERG.
